UNITED STATES PATENT OFFICE.

JUSTUS HATTEMER, OF CLIFFSIDE, NEW JERSEY, AND LOUIS C. KAULING, OF BROOKLYN, NEW YORK, ASSIGNORS TO PREMIER GRAND PIANO CORPORATION, OF NEW YORK, N. Y., A CORPORATION OF NEW YORK.

WIRELESS RECEIVING INSTALLATION FOR GRAND PIANOS.

Application filed May 27, 1924. Serial No. 716,193.

This invention relates to wireless receiving installations and particularly to a wireless receiving installation which is adapted to be effectually combined with a musical instrument, such as a grand piano, and in which, while each is adapted to function independently of the other, one forms part of and is necessarily dependent upon certain features of the other for operation.

10 The primary object of this invention is to enable a wireless receiving installation to be effectually concealed within the case of a grand piano without outward visible evidence of its presence therein.

15 A further object is to enable wireless receiving apparatus to be installed within a grand piano so that it may be bodily withdrawn from concealment and presented to view for operation or otherwise without disturbing its operative connections or mechanism.

20 A still further object is to enable the case of a grand piano to be utilized as a cabinet for wireless receiving apparatus without altering the case.

25 A still further object is to effectually utilize parts of the grand piano as a necessary adjunct or adjuncts of wireless receiving apparatus.

30 A still further object is to enable the wireless receiving mechanism to be installed within the music drawer of a player grand piano and to improve the construction of the music drawer so that it may be effectually employed for this purpose as well as for its usual purpose as part of the player grand piano, and as well for assisting in the accomplishment of other objects of this invention.

35 A still further object is to provide a unitary electric connection and unitary electric conducting means for a plurality of electrically operated instruments or mechanism located in combined relationship within a musical instrument case but adapted to be operated selectively through a single source of electric energy supply.

40 With the above and other objects in view our invention consists in the features of construction and operation set forth in the following specification and illustrated in the accompanying drawings, in which

45 Figure 1 is a front elevation of a player grand piano constructed in accordance with

this invention in which the wireless receiving installation is concealed without outward 55 evidence of its presence.

Figure 2 is a side elevation of a player grand piano, partly broken away to illustrate one embodiment of the concealed wireless receiving installation forming part of the 60 grand piano shown in Figure 1.

Figure 3 is a top plan view of the player grand piano illustrating the wireless receiving installation in withdrawn or outward 65 position.

Figure 4 is a partial side view of the player grand piano as shown in Figure 3.

Figure 5 is a perspective view of the music drawer of a grand piano illustrating another 70 modification of the construction of the drawer.

Figure 6 is a transverse sectional view 75 through the music drawer shown in Figure 5, substantially on the line 6—6 thereof, with the shutter in an open position.

Figure 7 is a front view of the music drawer in still another modification illustrating the use of a grille at the front opening 80 in place of the shutter shown in Figures 5 and 6.

Figure 8 is a diagrammatic plan view of a 85 modification of the invention showing the unitary electric arrangement for both the piano player mechanism and wireless receiving installation.

In the drawings we have illustrated a grand piano, in this instance an electrically operated player grand piano. The case 1 of the grand piano is provided with a music drawer 2 slidably mounted upon longitudinal guides 3 at the lower portion of the body of the case 1. The drawer 2 is preferably divided into a plurality of compartments, designated 4, 5 and 6. The compartments 5 and 6 are adapted to provide a housing for the music roll tracking mechanism 7 and playing motor 8, respectively, and for other parts of the player mechanism with which the grand piano is equipped. The drawer 2 is adapted to be moved to open and closed 90 positions, as shown in Figures 4 and 2, respectively, and in this instance is constructed so that when closed it appears to be an integral part of the piano case 1.

100 The operative parts of the wireless receiving apparatus are adapted to be located sub-

stantially within the compartment 4 of the drawer 2 so that when the drawer is in its closed position no outward evidence of its presence is visible. Such wireless receiving apparatus includes preferably an amplifying reproducing device, which may be an electromagnetic device, designated 10, having an amplifying horn 11. In this instance we construct the amplifying horn so that it is 10 adapted to be disposed in a substantially horizontal position within the compartment 4, with the bell of the horn directed outwardly and upwardly beyond the end of the panel board at the front of the receptacle or drawer 2. The neck of the amplifying horn 11 is adapted to extend substantially through the rearward end 13 of the drawer 2 to afford connection for the electromagnetic reproducer device 10. The panel board 15 is adapted to be positioned within the compartment 4 above the amplifying horn 11, and this panel board 15 is provided with the usual points of location for the usual necessary operative parts of the wireless receiving apparatus which we dispose about the amplifying horn 11, entirely within the drawer 2, as illustrated generally at 9. These parts however constitute no part of the invention as such, and are not specifically described 30 herein.

Within the piano case 1, preferably at the rearward portion thereof, we locate one or more sources of electric energy for the wireless receiving installation, herein shown 35 as a plurality of batteries 16 and 17, which may be of any suitable number or character. The batteries 16 and 17 are provided with sets of electrical conductors 18 and 19, respectively, situated preferably at the lower portion of the piano case 1 and adapted to be 40 connected to points of contact for the wireless receiving apparatus, in this instance the vacuum tube conductor terminals 20 and electromagnetic amplifying reproducer terminals 21 which project through the rearward portion 13 of the drawer 2 to an accessible 45 position at the rear of the drawer. We provide sets of conductors 18 and 19 of such character that the same are suited to this invention, being flexible, and of sufficient length 50 and of such character that when the drawer 2 is in a closed or partly closed position, as for instance seen in Figure 2, the conductors are adapted to form into coils 22 and 23, 55 respectively, behind the drawer 2, so that the effective length of the conductors is adapted to be decreased. When the drawer 2 is in an open position, as seen in Figure 4, the conductors are adapted to be extended to increased length without producing any disturbance of any part of the installation.

By the construction and arrangement just described the wireless apparatus is adapted to be effectually concealed within the case of 60 the grand piano without any substantial al-

teration visible at the exterior so that there is no outward evidence of the presence of the wireless receiving apparatus. The wireless receiving apparatus is adapted to be bodily moved to withdrawn operative position for 70 use when desired without in any way effecting any disturbance of the operative connections or mechanism and when so withdrawn a person has presented to his view, and directly in convenient juxtaposition in front 75 of him, both the wireless receiving apparatus and the operating parts of the player mechanism of the piano, so that both are readily accessible, and either may be operated as 80 may suit the person's whim or choice, without opening any separate panels or compartments, thus greatly simplifying and improving the instrument for its practical use as a 85 source of entertainment without in any way detracting from its aesthetic appearance as an accessory of beauty to the premises in which it may be located.

Referring particularly to Figures 5 and 6, we have in this instance constructed the 90 music drawer 2 so that the portion of the front board 24 opposite the compartment 4 is equipped with a movable panel or shutter 25, suitably pivoted as shown at 26. The bell of the horn 11 is in this instance directed 95 outwardly to the front of the drawer 2 instead of to the top as in the modification previously described, so that the drawer may be maintained in a closed position during 100 operation of the wireless receiving apparatus. The shutter 25 is adapted to be moved to different positions, one of which is illustrated in Figure 6, to effect any desired modulation of the volume of sound emitted 105 through the amplifying horn, and in its normal position is adapted to cover the bell of the horn and, as well, to constitute the front 110 wall of the receptacle or drawer 2. In this modification bead mouldings 27 are preferably situated at various points on the front board 24, and these bead mouldings tend to 115 effect substantial concealment of the shutter 25, and hence, the wireless receiving apparatus.

In Figure 7 we illustrate a further modified construction of the music drawer front board 115 24, in which we also direct the amplifying horn to the front, as in Figure 6, but in which a suitable grille 28 is substituted for the pivoted shutter 25. The grille may be of removable character. Bead mouldings 29 are 120 also preferably used in this instance. In this modification, however, the presence of the wireless receiving apparatus is not entirely concealed, but in other respects the construction is like that already described.

Referring further to Figures 2, 3 and 4, we have illustrated the utilization of parts of the grand piano as a necessary adjunct of the wireless receiving apparatus. In this instance we arrange for a wireless receiving 130

apparatus requiring an aerial or antenna and adapt the string plate and its attached piano wires or strings, designated 30, as an aerial. As shown at 31 the string plate is suitably connected to the aerial connector 32 at the rearward side of the rearward drawer portion 13, by means of a lead in or conductor 33. This lead in is adapted to coil behind the drawer 2 in the same manner as the conductors 18 and 19, as seen in Figure 2.

Referring to Figure 8, we illustrate an application of the unitary electric connection for a plurality of electrically operated instruments associated in a combined relationship but adapted to be operated selectively through the same source of power. In this instance the batteries 16 and 17 are dispensed with and the necessary care and upkeep of the same are eliminated, and a suitable transformer device, designated 34, is substituted for the batteries. The electrically operated grand piano is equipped with a main power circuit, comprising circuit wires 35 adapted to supply electric energy to the transformer 34, as suitably indicated at 36, and to the suction motor 37 of the player mechanism of the piano, as suitably indicated at 38. The power wires 35 are adapted to extend to the exterior of the piano case 1 and terminate in a single connector 39, which may be a plug or other suitable device which is adapted to be connected to an electric circuit of the premises in which the instrument is located. The transformer 34 is of a type adapted to effect alteration of the current flow from the unitary source to a degree adaptable for use with the wireless receiving apparatus which differs from the degree required for the suction motor 37.

This unitary installation simplifies and improves the construction of the grand piano, and the construction is adapted to be used, as well, with instruments other than a grand piano, such for instance as an upright piano equipped with wireless receiving apparatus. A suitable switch 40 is provided at its customary location for effecting operation of the player mechanism of the piano. Suitable switches 41 and 42 are also provided at any suitable location for the conductors 43 and 44 leading from the transformer 34 to the amplifying reproducer mechanism 45 and vacuum tube connectors 46, respectively. The conductors 43 and 44 are adapted to form in coils when the music drawer 2 is in its inward or closed position as hereinbefore referred to.

In this instance the installation has also been shown as including the use of the string plate and strings 47 of the piano as an aerial, suitably connected to the wireless receiv-

ing apparatus, as by the lead in 48, which, also, is adapted to coil for the same purpose as the other conductors.

While the transformer device 34 has been illustrated herein as replacing all the batteries commonly used with a wireless receiving installation, it is understood that where a plurality of batteries of different voltage or other characteristics would ordinarily be used with the wireless receiving apparatus the transformer device 34 may be employed to eliminate but one set of batteries, such for instance as the wet or storage batteries, and such dry batteries as it may be desired to use may be suitably located within the piano case in the manner illustrated in Figures 2, 3 and 4.

What we claim is:

1. In a cabinet for a radio receiving installation, in combination, a stationary case, a shallow receptacle supported by said case, said receptacle arranged for movement in a horizontal plane away from said stationary case to an exposed position at the front of the case, said receptacle having rear and opposite side portions, an amplifying horn in said receptacle and movable therewith, said horn arranged to extend horizontally from said rear portion and between said side portions with its bell at the front of said receptacle, radio receiving apparatus disposed about said amplifying horn, a stationary source of electric energy in said case, and devices connecting said stationary source of electric energy with the radio receiving apparatus in said movable receptacle in both closed and open positions of said receptacle.

2. A cabinet for radio apparatus comprising, in combination, a stationary case, a shallow receptacle mounted to slide in a horizontal plane toward and away from said stationary case, said receptacle having rear and opposite side portions, radio receiving apparatus in said receptacle, said radio receiving apparatus including an amplifying horn extending horizontally from said rear portion and between said side portions with the bell of said horn at the front of said receptacle, a closure for the front of said receptacle, said closure displaceable in all positions of said receptacle, a stationary source of electric energy in said case, and devices connecting said stationary source of electric energy with the radio receiving apparatus in said sliding receptacle in all positions of the latter.

In testimony whereof, we have signed this specification.

JUSTUS HATTEMER.
LOUIS C. KAULING.
